UNITED STATES PATENT OFFICE.

VICTOR VIVAUDOU, OF NEW YORK, N. Y.

DESIGN FOR A POWDER-CAN.

51,446.

Specification for Design.

Patented Oct. 30, 1917.

Application filed April 12, 1916. Serial No. 90,785. Term of patent 7 years.

To all whom it may concern:

Be it known that I, VICTOR VIVAUDOU, a citizen of France, residing at the borough of Manhattan, in the county, city, and State of New York, have invented a new, original, and ornamental Design for a Powder-Can, of which the following is a specification, reference being had to the accompanying drawing, forming part thereof.

Figure 1 is a top plan view of a powder can showing my new design.

Fig. 2 is a front view.

Fig. 3 is an end view.

I claim:

The ornamental design for a powder can as shown.

VICTOR VIVAUDOU.
